(54) HATS, BODIES, BATS

(76) Inventor: **Stephen Hurlbut**

Stephen Hurlbut
Letters Patent

The Schedule referred to in their Letters Patent and making part of the same containing a description in the words of the said Stephen Hurlbut himself of his Improvement in making and constructing Bats for Hat Bodies

It is known that Stephen Hurlbut of Glastonbury in the County of Hartford and State of Connecticut have invented a new and useful improvement in making and constructing Bats for hat bodies and that the following is a full and exact description of the construction and operation of the said machine as invented improved by me. First an Apron (No 3) attached to a common carding machine, which is made to vibrate by means of a Crank-pully (No 6) belted from the Doffer (No 2) A standard (No 5) is affixed to a cage (No 4) underneath the apron and by a link (No 12) from the standard to which link the crank-pully is attached, the size of the Bat is regulated it being necessary to lengthen the crank to increase the size and to shorten it to lessen the size. The apron is made to move round the frame in order to carry the web from the Doffer to the Turner (No 4) by means of a belt ascending from a pulley on the end of the Doffer (opposite the crank-pully) above to a double pulley (No 13) thence descending to the pulley of the apron. The Turner is a light wheel or table having a horizontal rotary motion and on the turner is a roller (No 5) The frame (No 4) is moved by a belt running on a pulley attached to the under side of the Turner, thence to another pulley on the frame of the carding machine which last pulley is carried by a belt on the shaft of the main engine. The roller is attached by a swivel in its center to the web of the Turner, and its outer or extreme end is secured to the frame of the carding machine by means of a screw and wire. The operation of the machine is as follows. The web is received from the Doffer of a common carding machine upon the apron, it is carried by the apron to the Turner and by the vibratory motion of the apron the web is opened as it is received between the Turner and the roller. The variation in thickness of the bat for the formation of the body must be regulated by the feed of the carding machine. The size of the bat for the formation

of this body is regulated by a limb from the Standard of the Apnor, to which there is a crank pulley. When the hat is completed it is torn from the circumference of the centre, gradually rolled over, and following the former through one of its evolutions is taken off without stopping the machinery. The hat is then divided into three equal parts which form three hat bodies. My claim for a patent is to the whole of the foregoing description attached to the Carding Machine and for carding the webbing and making the hat.
